[57] CLAIM

The ornamental design for a string tie, as shown.

DESCRIPTION

FIG. 1 is a front view of the string tie ornamental design of

the present invention;

FIG. 2 is an enlarged front view of a portion of the tie including the tie clip;

FIG. 3 is an enlarged rear view of a portion of the tie including the tie clip;

FIG. 4 is a right side view of a portion of the tie inculding the tie clip;

FIG. 5 is a left side view of a portion of the tie including the tie clip;

FIG. 6 is a view of the top of the tie clip showing the tie string in section;

FIG. 7 is a view of the bottom of the tie clip showing the tie string in section;

FIG. 8 is an enlarged side view of one of the two identical tie string ends;

FIG. 9 is a front view, which is identical to a back view, of the pair of tie string ends, showing a portion of the tie string;

FIG. 10 is a top view of the tie string ends without the strings; and,

FIG. 11 is a bottom view of the tie string ends.

The broken line showing of indicia in FIGS. 1 and 2 is for illustrative purposes only and forms no part of the claimed design.
